United States Patent Office

Des. 202,850
Patented Nov. 9, 1965

202,850

LOG-REST

Gerald L. Jonas, 172 Clara St., San Francisco, Calif.

Filed Nov. 2, 1964, Ser. No. 82,434

Term of patent 14 years

(Cl. D81—18)

FIG. 4

FIG. 5

FIG. 2

FIG. 3

FIG. 1

I claim:

The ornamental design for a log-rest, as shown.
